APPARATUS FOR OXIDIZING REACTIONS

Edwin N. Richards, Cincinnati, Ohio, assignor to
The Standard Oil Company, Cleveland, Ohio, a
corporation of Ohio

Application October 23, 1940, Serial No. 362,471

5 Claims. (Cl. 23—252)

In the operation of oxidizing reactions with an oxygen-providing gas, air or pure oxygen, some materials react exothermically and some endothermically. Where the reaction is of exothermic character, the temperature rise in the material from the oxidizing action may be of undesirable extent, particularly where the material is being operated upon in considerable mass. Under such circumstances, it has been customarily necessary to carefully watch the temperature and occasionally interrupt the operation in order to prevent rise into a range destructive of the material. The loss of time so occasioned adds to the cost of production, and it is undesirable in general from a manufacturing standpoint. In accordance with the present invention, oxidizing reactions of endothermic or exothermic character may be conducted equally well in the same apparatus, and for operations involving heat generation an exact control may be had on the temperature such as to make possible the carrying on of the operation without interruptions on account of excessive temperature rises.

To the accomplishment of the foregoing and related ends, the invention, then, comprises the features hereinafter fully described, and particularly pointed out in the claims, the following description and the annexed drawing setting forth in detail certain illustrative embodiments of the invention, these being indicative however, of but a few of the various ways in which the principle of the invention may be employed.

In said annexed drawing:

Fig. 1 is a perspective view, partly in section, showing an embodiment of the invention; and Figs. 2 and 3 are enlarged sectional details.

A container 2, of size and proportions desired, is of a character having a heat-conducting wall, and is closed above, except for an outlet pipe 3 for discharge of gasiform products, etc.; and safety-opening means 4 may be provided if desired, to release pressure in event of internal explosion. Spaced away from the heat-conducting wall, as by suitable supports 6, is a heat-insulating jacket 7, thus providing a flue space against the metallic or heat-conducting wall, and in turn insulatingly closed over by the jacket. Projections in form as desired, as for instance outstanding ribs 8 may be provided on the metal wall to increase the heat dissipation. The flue space has openings or ports 10 at the top, and openings or ports 11 at the bottom. The upper ports are guarded by covers 12, desirably mounted in such manner as to be controllably movable. For instance, the covers may be hinged as at 13, and a remote control actuating means may be provided, as for example an angular arm 14 extending from the cover, and flexible means, as a cable or chain 15 from such angular arm provides operation of the cover from the operating

floor which may be at a distance of many feet below. Such ports and covers may be arranged as desired, depending somewhat upon the size of the apparatus. The lower ports are guarded by covers 17, which again may be mounted for convenient operation. For instance, they may be hinged as at 18, and may have operating means as desired. One convenient arrangement is a means for normally holding the cover closed, such as weight arms 19, and hooks 16 may be hooked into a link of the lower end of chain 15 to hold the cover up when in open position. As many ports and covers may be arranged as desired or appropriate for the size of the apparatus.

As seen, when the upper and lower ports are closed, the apparatus is heat-insulated, and an oxygen-providing gas introduced into the container through suitable means, as for example a bottom perforated coil system 20, permits operation upon material in the apparatus, while guarded against heat loss. By opening the covers 12 and 17 as extensively as desired however, the flue system against the heat-conducting wall may be put into operation, and material being treated in the apparatus is then subject to heat removal to the extent desired. Materials operating by either endothermic or exothermic reaction may thus be treated appropriately, and for materials of the latter character the temperature may be controlled as desired by appropriate opening and closing of the ports. Where the material being treated is for instance an asphaltic petroleum residuum for conversion into asphalt, the operation may be started with the ports closed, and as the temperature rise necessitates, the ports may be appropriately opened to the extent required to control the temperature in the range desired without detrimental runaway and necessity of discontinuing the oxidation. Equally convenient also, are operations on such materials as hydrocarbons to be oxidized for production of oxidation acids; or other materials variously.

Other modes of applying the principle of the invention may be employed, change being made as regards the details described, provided the features stated in any of the following claims, or the equivalent of such, be employed.

I therefore particularly point out and distinctly claim as my invention:

1. Apparatus for oxidizing reactions, comprising a container having a heat-conducting wall, heat-radiating projections on the exterior of said wall, a heat-insulating wall spaced externally from said wall to provide a flue space, a circuit of ports about the top and a circuit of ports about the bottom of such flue space, hinge-mounted covers on the top ports, operating chains depending from said covers, hinge-mounted covers on the bottom ports, and means for connecting said

latter covers adjustably to said chains to simultaneously hold top and bottom covers open and adjust the amount of opening of the bottom covers.

2. Apparatus for oxidizing reactions, comprising a container having a heat-conducting wall, a heat-insulating jacket spaced externally from said wall to provide a flue space, ports at the top and bottom of such flue space, hinge-mounted covers on the top ports, hinge-mounted covers 10 on the bottom ports, angular arms extending from the top covers, chains suspended from said arms, weighted arms out-standing from said bottom covers, and hook means on said last-named arms engageable with links of said chains to hold both covers open.

3. Apparatus for oxidizing reactions, comprising a container having a heat-conducting wall, a heat-insulating jacket spaced externally from said wall to provide a flue space, ports at the top 20 and bottom of such flue space, hinge-mounted covers on the top ports, chains extending from said top covers toward the floor, hinge-mounted covers on the bottom ports, and means for engag-

ing the chains with the bottom covers to hold the same open.

4. Apparatus for oxidizing reactions, comprising a container having a heat-conducting wall, a heat-insulating wall spaced externally from said wall to provide a flue space, a circuit of ports about the top and a circuit of ports about the bottom of such flue space, hinge-mounted covers on the top ports, hinge-mounted covers on the bottom ports, and adjustable means whereby top and bottom covers can be simultaneously held open and whereby the amount of opening of the bottom covers can be adjusted.

5. Apparatus for oxidizing reactions, comprising a container having a heat-conducting wall, a heat-insulating wall spaced externally from said wall to provide a flue space, ports at the top and bottom of such flue space, covers on both sets of ports, and adjustable means attached to the top covers, and means on the bottom covers for disengageably attaching the adjustable means to the bottom covers whereby to hold both covers open simultaneously.

EDWIN N. RICHARDS.
